UNITED STATES PATENT OFFICE

140,041

DESIGN FOR A POMPON ORNAMENT FOR SHOES, OR SIMILAR ARTICLES

Forrest P. Moore and Matilda C. Moore,
Ontario, Calif.

Application November 2, 1944, Serial No. 116,107

Term of patent 7 years

(Cl. D7—6)

To all whom it may concern:

Be it known that we, Forrest P. Moore and Matilda C. Moore, citizens of the United States of America and residents of Ontario, San Bernardino County, California, have invented a new, original, and ornamental Design for a Pompon Ornament for Shoes, or Similar Articles, of which the following is a specification, reference being had to the accompanying drawing, forming part thereof.

Fig. 2 is an edge view thereof.

We claim:

The ornamental design for a pompon ornament for shoes, or similar articles, substantially as shown.

FORREST P. MOORE.
MATILDA C. MOORE.
